Clarence W. Stricker Inventor

Walker H. Murray Attorney

UNITED STATES PATENT OFFICE.

CLARENCE W. STRICKER, OF CINCINNATI, OHIO, ASSIGNOR TO THE DALY MANUFACTURING COMPANY, OF CINCINNATI, OHIO, A CORPORATION OF OHIO.

PUFF IRON.

Application filed July 9, 1920. Serial No. 394,959.

To all whom it may concern:

Be it known that I, CLARENCE W. STRICKER, a citizen of the United States of America, and resident of Cincinnati, in the county of Hamilton and State of Ohio, have invented a new and useful Improvement in a Puff Iron, of which the following is a specification.

An object of my invention is to provide 10 a puff iron that will not project a spray of water when steam is emitted therefrom for the purpose of spraying the garment that is being pressed.

Another object is to provide a device for 15 the purpose stated that is positive in operation and is simple in construction and manipulation.

These and other objects are attained by the means described herein and disclosed in 20 the accompanying drawing in which:

Fig. 1 is a transverse sectional view of a device embodying my invention.

Fig. 2 is an enlarged sectional view on line 2—2 of Fig. 1.

25 My invention contemplates providing means for emitting a spray of steam from the puff iron head A, the said means being so constructed and related to the steam heating system employed with the head A that 30 some of this steam may be released, yet no products of condensation will be discharged with the steam.

The puff iron A is of the usual shape and construction, having a spray chamber a in 35 its top, and having a perforated plate or spray nozzle a' over the chamber a, such plate or spray nozzle forming part of the face of the iron head. The chamber a does not communicate directly with the main 40 chamber a² within the puff iron head A. The head A is mounted upon a support pipe B, the bore b of the pipe communicating with the main chamber a² and with a boiler, not shown.

45 A valve C is interposed in the pipe B and is adapted to control the flow of steam thru the tube d extending thru the support pipe B, thru the head A and communicating at its upper end with the spray chamber a.

50 Normally the lower end of the tube d is sealed by the valve C. The valve C comprises a housing c, a reciprocating valve stem C' within the housing and having a valve member c² formed thereon, a spring 55 c³ engaging the collar c' on the valve stem

and the housing and adapted to normally close the valve, and a lever c⁴ having a handle c⁶, by means of which the valve may be opened. The valve member c² normally engages the valve seat c⁵ formed on the housing C. The duct c⁸ in the housing C and about the one end of which is formed the valve seat c⁵, communicates with the lower end of the bore d' in the tube d. The pipe B may be mounted upon a hollow base E 60 the chamber e of which communicates with a boiler, not shown.

65 The operation of my device is as follows:

Normally the steam from the boiler passes thru the hollow base E and the pipe B and 70 into the main chamber a² in the puff iron head thereby keeping the head hot at all times. When a garment that is being pressed is to be sprayed, the handle c⁶ upon the lever c⁴ is pushed inward upon the valve 75 stem C' thereby unseating the valve member c² and permitting steam to pass thru the duct c⁸ and tube d into the spray chamber a and thru the perforations a³ in the plate a' until the garment has been sufficiently sprayed. Then the handle c⁶ is released and the spring c³ operating upon the collar c' formed on the valve stem, seats the valve member c² upon the valve seat c⁵ thereby closing off communication between the 80 spray chamber a and the boiler. Because the spray steam is withdrawn directly from the supply of steam coming from the boiler, and because there is no possibility of condensation forming about the valve or in the 85 tube d, steam only will be emitted upon the garment. Should it develop from any unknown cause that some water did enter the valve, the valve housing and the tube being hot from the steam, such water will vaporize and pass out of the spray nozzle or be emitted when next the valve is operated. This vaporization within the tube proceeds 90 because of the fact that practically none of the cool outside air can reach the lower part of the tube and thereby retain the water in this form. Any air that would or could enter the tube would be hot by the time it reached the lower part of the tube.

95 What I claim is:

100 1. In a puff iron the combination with a head having a steam chamber therein and a steam spray discharge nozzle upon the face of the head whereby a spray chamber 105 is formed between the head and the nozzle, 110

of a tube extending through the steam chamber in the head and communicating at one end with the spray chamber, and a valve controlling the admission of steam to the tube.

2. In a device of the class described the combination of a hollow head, a pipe adapted to carry steam into the head, a tube extending thru the chamber in the head, exposed at one end to the atmosphere and having its other end disposed within the pipe, a valve at the second mentioned end of the tube controlling the admission of steam into the tube, and a spray nozzle for the first mentioned end of the tube.

3. In a device of the class described the combination with a puff iron having a chamber to receive steam of a nozzle mounted on the puff iron whereby to form a spray chamber between itself and the puff iron, and a tube communicating at one end with the spray chamber and extending thru the puff iron chamber, whereby the tube and the walls of the spray chamber may be kept hot by steam in the puff iron chamber, and a valve remote from the puff iron chamber controlling admission of steam to the tube.

4. A puff iron comprising a head, a base, a support pipe connecting the head and the base, a steam discharge nozzle upon the head, a chamber being formed between the head and the nozzle, a tube extending from the chamber through the head and into the support pipe, and a valve interposed in the support pipe and controlling communication between the tube and the pipe.

5. In a device of the class described the combination of a hollow puff iron having a depression in its wall, a perforated plate above the depression whereby a chamber is formed between the plate and the puff iron wall, said chamber being separate and non-communicating with the interior of the puff iron, means whereby steam may be admitted to the puff iron, a tube within the puff iron adapted to be kept hot by steam in the puff iron, communicating with the chamber between the plate and the puff iron wall, and a valve controlling admission of steam to the tube at a place remote from the puff iron.

In witness whereof, I have hereunto subscribed my name this 7th day of July, 1920.

CLARENCE W. STRICKER.
